DESIGN FOR AN ILLUMINATED WREATH ORNAMENT

Bernard F. Muldoon, Mountainview, N. J., assignor to Henry Hyman, Brooklyn, N. Y.

Application November 25, 1936, Serial No. 66,136

Term of patent 7 years

To all whom it may concern:

Be it known that I, Bernard F. Muldoon, a citizen of the United States, residing at Mountainview, in the county of Passaic and State of New Jersey, have invented a new, original, and ornamental Design for an Illuminated Wreath Ornament, of which the following is a specification, reference being had to the accompanying drawing, forming part thereof, in which

Fig. 1 is a front elevational view of an illuminated wreath ornament showing my new design; and

Fig. 2 is an edge view thereof.

I claim:

The ornamental design for an illuminated wreath ornament, as shown.

BERNARD F. MULDOON,
